UNITED STATES PATENT OFFICE.

GEORGE W. LYONS, OF ORANGE, CONNECTICUT, ASSIGNOR OF THREE-FOURTHS TO
ABRAHAM L. NOTKINS, JAMES A. NOTKINS, AND MATTHEW A. NOTKINS, ALL OF
NEW HAVEN, CONNECTICUT.

LEVEL.

1,205,946.

Specification of Letters Patent. Patented Nov. 21, 1916.

Application filed April 16, 1915. Serial No. 21,808.

To all whom it may concern:

- Be it known that I, GEORGE W. LYONS, a citizen of the United States, residing at Orange, in the county of New Haven and 5 State of Connecticut, have invented certain new and useful Improvements in Levels, of which the following is a specification, reference being had therein to the accompanying drawings.
- 10 My invention relates to a new and improved level, having for its object, among other things, to so construct the same that it may be collapsible and occupy the minimum space when not in use.
- 15 To these, and other ends, my invention consists in the level, having certain details of construction and combinations of parts, as will be hereinafter described and more particularly pointed out in the claim.
- 20 Referring to the drawings, in which like numerals of reference designate like parts in the several figures, Figure 1 is a perspective view of my improved level complete; Fig. 2 is an enlarged fragmentary view 70 thereof; and Fig. 3 is an end view of the central section.

My improved level is constructed with three sections 1 and 2—2, all of which are provided with end caps 3 to minimize the 30 wear thereon. The section 1 is provided with a spirit level 4 and sections 2 with spirit levels 5, all being of the ordinary construction and mounted within apertures 6 as is customary.

35 Extending loosely through an aperture in the section 1 is a tie bar 7, terminating at each end in a threaded shank 8 which projects beyond the end caps 3 and upon which are the nuts 9 and washers 10. Also fixed 40 in the opposite ends of the section 1, and projecting beyond the caps 3, are the dowel pins 11, which project into blocks 12 fixed in the sections 2—2. These dowel pins when they register with the opening in the blocks 45 12, as shown in Fig. 2, insure the proper alignment of the sections, which are then secured together by the washers 10 and nuts 9, which latter are threaded upon the shanks through the openings 13.

50 In operation the sections are assembled

by passing the shank 8 of the tie bar 7 through the end of the section 2 and permitting the dowel pins 11 to enter the blocks 12, afterward placing the washer 10 and nut 9 upon the shank and tightening the latter by a wrench that operates within the opening 13. When the sections are secured in this manner they all become a unitary structure and are capable of use as is the usual level. The level is taken down, for 60 convenience in transportation or for other reasons, by separating the sections 2 from the section 1, thus materially shortening the length of the level and the space that it would otherwise occupy. 65

In minor details my invention may be considerably modified, and I would therefore have it understood that I do not limit myself to the exact construction herein shown and described, but claim all that falls fairly 70 within the spirit and scope of my invention, as set forth in the appended claim.

Having described my invention, what I claim as new and desire to secure by Letters Patent, is:— 75

In a level, the combination with a central section, having a longitudinal aperture therethrough; of a member, substantially rectangular in cross section, within said aperture, and by its engagement therewith held against rotation, said member having a threaded shank at each end which projects beyond the ends of said section; a dowel pin fixed in each end of said section and projecting outwardly therefrom; companion 85 end sections, each having a transverse opening therethrough between its ends and a longitudinal opening extending from one end to said transverse opening, with one or more blocks fixed in the end having the longitudinal opening therein; and a nut secured upon each of the threaded shanks of the member connected with said central section, said nuts being within the transverse opening. 90

In testimony whereof I affix my signature 95 in presence of two witnesses.

GEORGE W. LYONS.
